UNITED STATES PATENT OFFICE.

JAMES G. LAWLER, OF ST. CHARLES, MISSOURI, ASSIGNOR TO AMERICAN CAR AND FOUNDRY COMPANY, OF ST. LOUIS, MISSOURI, A CORPORATION OF NEW JERSEY.

UPPER BUFFING DEVICE FOR VESTIBULE FACE-PLATES.

1,170,548.

Specification of Letters Patent.

Patented Feb. 8, 1916.

Application filed March 16, 1915. Serial No. 14,854.

To all whom it may concern:

Be it known that I, JAMES G. LAWLER, a citizen of the United States, residing at St. Charles, Missouri, have invented a certain 5 new and useful Improvement in Upper Buffing Devices for Vestibule Face-Plates, of which the following is a full, clear, and exact description, such as will enable others skilled in the art to which it appertains to 10 make and use the same, reference being had to the accompanying drawings, forming part of this specification.

My invention relates generally to railway car vestibules and more particularly to the 15 means employed for maintaining the upper portions of the diaphragm face plates of vestibules in proper position or in restoring them to such position when they have been displaced or shifted as a result of relative 20 movement between the cars to which the diaphragms are applied as said cars pass over curves, crossings, and irregularities in the track.

Devices of the character to which my invention relates are usually known as upper buffing devices for vestibule face plates, and generally include a spring, preferably of the semi-elliptic type, and composed of one or more leaves, which spring is interposed 25 30 between the face plate of the diaphragm and the end of the car, and which, in service, is compressed and expands with the corresponding movements of the diaphragm, thus at all times, maintaining the face plates of 35 an adjacent pair of diaphragms in close yielding contact with each other.

The principal object of my invention is to provide comparatively simple and inexpensive connecting means between the semi- 40 elliptic spring, the diaphragm face plate and the vestibule structure, which means is particularly effective in resisting the outward swinging movement of the upper portion of 45 said diaphragm face plate.

45 The connecting means contemplated by my invention includes spring bearings or brackets, each formed in two parts and readily detachable in order to permit the spring to be easily and quickly removed and 50 repositioned for use as may be required when the diaphragm or parts thereof are undergoing repairs.

With the foregoing and other objects in view, my invention consists in certain novel

features of construction and arrangement of 55 parts, hereinafter more fully described, claimed and shown in the accompanying drawings, in which—

Figure 1 is a front elevational view of the upper portion of a diaphragm face plate 60 and showing the brackets which serve as bearings for the upper buffering spring which is attached to said face plate. Fig. 2 is a plan view of the diaphragm and its spring 65 and showing one of the spring bearings or brackets in horizontal section. Fig. 3 is an enlarged horizontal sectional view taken through the center of one of the spring bearings or brackets. Fig. 4 is an enlarged vertical section taken approximately on the 70 line 4—4 of Fig. 1. Fig. 5 is a detail elevational view of a portion of the rear plate of one of the brackets and showing one of the bolt receiving apertures therein. Fig. 6 is an enlarged vertical section taken approximately 75 on the line 6—6 of Fig. 2. Fig. 7 is a horizontal section taken approximately on the line 7—7 of Fig. 6. Fig. 8 is a side elevational view of a modified form of the 80 spring receiving bracket or bearing. Fig. 9 is a horizontal section taken approximately on the line 9—9 of Fig. 8.

Referring by numerals to the accompanying drawings, 10 designates the end portion 85 of a car vestibule, 11 the usual bellows diaphragm, and 12 the usual face plate of said diaphragm. An ordinary semi-elliptic spring 13 having one or more leaves is provided at its center with an encircling band 14, the same being fixed to said spring in 90 any suitable manner, preferably by welding, and the rear portion of said band is provided with a vertically disposed rib 14^a which is preferably semi-circular in horizontal section. Fixed in any suitable manner to the upper central portion of the face plate 12 is a plate 15 provided with a centrally arranged vertically disposed bearing 15^a which receives the rib 14^a on band 14, and the lower portion of said plate 15 is provided with a horizontally disposed flange 15^b. Hinged to the outer end of this flange 95 is the lower end of a vertically disposed bar 16, the upper end of which is detachably secured in any suitable manner, preferably by 100 means of a bolt 16^a to the upper end of plate 15. This construction provides a firm support for the central portion of the spring, 105

which support can be readily opened to permit the removal or insertion of the spring and the bearing 15^a which receives the rib 14^a permits the central portion of said spring to rock slightly as may be required in service, and at the same time, said spring is held against longitudinal movement through the bracket or support which comprises the plates 15 and 16.

10 The bracket contemplated by my invention and which serves as a combined keeper and bearing for the end of the spring includes a base member 17, preferably in the form of a flat plate which is rigidly fixed in 15 any suitable manner, preferably by means of rivets to the vestibule structure, and the lower portion of said plate is bent outwardly and thence downwardly to form a portion 18 which is parallel with and offset from 20 the main body portion of the plate. Formed through this offset portion 18 is one or more rectangular openings 19 of sufficient size to receive a bolt head and depending from each opening 19 is a bolt receiving notch or recess 20.

25 Hinged in any suitable manner to the upper end of each plate 17 is the upper end of a vertically disposed rod or bar 21, the lower end of which is adapted to overlie and 30 bear directly against the offset portion 18 of plate 17. Formed through the lower portion of member 21 are bolt holes which are 35 adapted to coincide with the notches 20 and seated therein are bolts 22, the forward ends of which receive nuts 23 and the heads of said bolts being of such size as to be readily inserted through the openings 19.

40 The main body portion of the member 21 occupies a position directly in front of the plate 17 and the end portion of the spring 45 13 is positioned between these parts, it being understood that the extreme outer end of the spring is bent outward as designated by 13^a in order to form a stop to limit the inward movement of the end portion of the spring 45 and the consequent outward movement of the central portion thereof.

50 To release the ends of the spring 13 when it is desired to remove the diaphragm face plate, it is only necessary to remove the nuts 23 on the forward ends of bolts 22 and this permits members 21 to be swung outwardly and upwardly.

55 When the members 21 are swung downward and connected to the base plates 17 by tightening the nuts 23 on bolts 22, the end portions of the spring are maintained in proper position against the vestibule and inasmuch as the ends of said spring are thus 60 retained, the upper portion of the diaphragm face plate to which the central portion of the spring is connected is maintained in proper operative position and held against outward swinging movement. To release the central portion of the spring from the dia-

phragm face plate, it is only necessary to remove bolt 16^a and swing the plate 16 downward.

65 In the modified construction illustrated in Figs. 7 and 8, the lower end of base plate 17^a is bent outward into a substantially horizontal plane as designated by 17^b, said outwardly bent portion being slotted to receive the lower end of bolt 21^a, the latter being hinged at its upper end to the upper portion 70 of plate 17^a, and its lower end carrying a nut 21^b, which is positioned beneath the outwardly bent portion 17^b. In this construction a washer is preferably interposed between nut 21^b and the outwardly bent portion 80 17^b.

85 In service it will be understood that the spring 13 yieldingly resists the inward movement of the face plate 12 and during such action, the ends of said spring move freely 90 through the spaces between the plates 17 and their hinged members 21.

95 While I have shown and described the upper buffering spring as being connected at its center to the diaphragm face plate and spring end retaining brackets or keepers on the vestibule structure, it will be understood that the positions of these parts may be reversed, that is, with the center of the spring connected to the vestibule structure and the 95 brackets or keepers secured to the diaphragm face plate.

A device of my improved construction is comparatively simple, can be cheaply manufactured and installed, provides a substantial connection between the buffering spring, the face plate, and the vestibule structure, permits the end portions of the spring to move freely in both directions as said spring is compressed and expands, permits the central portion of the spring to have slight rocking movement on the vertical axis, and in the event of repairs or renewal of the diaphragm or its parts, the hinged portions of the bearings can be easily and quickly released to permit the removal of the spring.

It will be readily understood that minor changes in the size, form and construction of the various parts of my improved device can be made and substituted for those herein shown and described, without departing from the spirit of my invention, the scope of which is set forth in the appended claims.

I claim:

1. The combination with a railway car vestibule and vestibule diaphragm face plate, of a semi-elliptic spring secured to one of said elements, and spring retaining members fixed to the other element, each of which retaining members comprises a base plate and a keeper hinged thereto.
2. The combination with a railway car vestibule and vestibule diaphragm face plate, of a semi-elliptic spring secured to one of said elements, and spring retaining 130

members fixed to the other element, each of which retaining members comprises a base plate and a keeper hinged thereto, and means for securing the free end of the 5 keeper to the base plate.

3. The combination with a railway car vestibule and vestibule diaphragm face plate, of a semi-elliptic spring secured to one of said elements, and retaining members 10 for the end portions of said spring, each of which members comprises a pair of plates hinged to each other, one of said plates being rigidly fixed to the other one of the first mentioned elements.

15 4. A diaphragm face plate spring retaining device comprising a bearing plate, and a keeper hinged thereto, said parts being spaced apart to form a spring pocket.

5. A diaphragm face plate spring retaining device comprising a bearing plate, a keeper hinged thereto, said parts being spaced apart to form a spring pocket, and readily releasable means for securing the 20 free end of the keeper to the bearing plate.

25 6. A diaphragm face plate spring retaining device comprising a pair of plates hinged to each other, said plates being spaced apart to form a spring pocket, and a spring bearing formed on one of said 30 plates.

7. In a device of the class described, the combination with a diaphragm face plate spring provided with an encircling band, of a spring support comprising a pair of plates 35 hinged to each other and spaced apart so as to receive the band on the spring, and readily releasable means for maintaining said plates in closed position.

40 8. The combination with a diaphragm face plate spring provided near its center with a vertically disposed bearing rib, of a

spring support comprising a pair of plates hinged to each other, one of which plates is provided with a bearing adapted to receive the bearing rib on the spring, and readily 45 releasable means for maintaining said plates in closed position.

9. The combination with a railway car vestibule and vestibule diaphragm face plate, of a semi-elliptic spring arranged between 50 said elements, and spring retaining members fixed to said elements and engaging the ends and central portion of the spring, each of which retaining members comprises a pair of plates hinged to each other, and readily releasable means for maintaining said plates in closed position.

10. The combination with a railway car vestibule and vestibule diaphragm face plate, of a semi-elliptic spring interposed 60 between the face plate and vestibule, and spring retaining members fixed to said vestibule and face plate, each of which retaining members comprises a base plate, and a keeper hinged thereto. 65

11. The combination with a railway car vestibule and vestibule diaphragm face plate, of a semi-elliptic spring interposed between the face plate and vestibule, spring retaining members fixed to said vestibule 70 and face plate, each of which retaining members comprises a base plate, and a keeper hinged thereto, and means for maintaining said plates in closed position.

In testimony whereof I hereunto affix my 75 signature in the presence of two witnesses, this second day of March, 1915.

JAMES G. LAWLER.
